US00D997951S

(12) United States Design Patent (10) Patent No.: US D997,951 S
Chen (45) Date of Patent: * Sep. 5, 2023

(54) LAPTOP COMPUTER

(71) Applicant: Lenovo (Beijing) Limited, Beijing (CN)

CN 307094742 S 2/2022

(72) Inventor: Xi Chen, Beijing (CN)

FOREIGN PATENT DOCUMENTS

(73) Assignee: Lenovo (Beijing) Limited, Beijing (CN)

Notice of Restriction Requirement of the U.S. Appl. No. 35/514,668, dated May 4, 2023.

() Term: 15 Years

(21) Appl. No.: 35/514,656

Primary Examiner — Keli L Hill

(22) Filed: May 5, 2022

Assistant Examiner — Harold E Blackwell, II

(80) Hague Agreement Data

(74) Attorney, Agent, or Firm — Oppedahl Patent Law Firm LLC

Int. Filing Date: May 5, 2022

CLAIM

Int. Reg. No.: DM/221692

The ornamental design for a laptop computer, as shown and described.

Int. Reg. Date: May 5, 2022

DESCRIPTION

Int. Reg. Pub. Date: Jul. 8, 2022

1. Laptop computer
2. Laptop computer
